UNITED STATES PATENT OFFICE.

WALTER C. WESTAWAY, OF BELVIDERE, ILLINOIS.

INTERNAL-COMBUSTION ENGINE OR THE LIKE.

1,031,754.

Specification of Letters Patent.

Patented July 9, 1912.

Application filed June 30, 1911. Serial No. 636,816.

To all whom it may concern:

Be it known that I, WALTER C. WESTAWAY, a citizen of the United States, residing at Belvidere, in the county of Boone and State of Illinois, have invented certain new and useful Improvements in Internal-Combustion Engines or the Like, of which the following is a description:

My invention belongs to that general class 10 of devices known as internal combustion engines or the like, and relates particularly to an improved intake valve and mixer for controlling the combustible supply and for mixing or commingling the charge.

15 My invention has among its objects the production of a device of the kind described that is more efficient, durable and satisfactory that may be manufactured and installed economically, either during the 20 course of construction of the engine; or applied to engines previously constructed to replace the devices thereon.

To this end my invention consists in the 25 novel construction, arrangement and combination of parts herein shown and described and more particularly pointed out in the claims.

In the drawings, wherein like reference 30 characters indicate like or corresponding parts, Figure 1 is a sectional view of one form of my device. Fig. 2 is a section of the same taken substantially on line 2, 2 of Fig. 1. Fig. 3 is a sectional view of another form of my device. Fig. 4 is a sectional view of a modified form of my device, showing the application to a two-cycle engine, and Fig. 5 is a sectional view of a portion of an engine, showing a modified form of my device applied thereto.

40 Broadly, my invention consists in providing suitable mechanism for admitting a predetermined amount of air to the interior of the cylinder, or to the combustion chamber with the ingoing mixture or charge, and 45 also in providing mixing means at the intake port or proximate thereto, whereby the ingoing charge and the additional air are co-mixed or co-mingled before firing.

Referring to the construction shown in 50 Figs. 1 and 2, 1 represents the cylinder wall, which may be provided with a water jacket 2, forming a water space 3, 4 being the usual intake port or opening through the cylinder wall at any desired point in the cylinder.

55 At the intake port is arranged an intake

valve 5, provided with a face 6, arranged to cooperate with the valve seat 7 on a casing 8, within which is formed a chamber 9. The casing 8 may be secured to the engine cylinder in any suitable way, as shown, it is 60 flanged at 10 and secured thereto by bolts 11. The charge or mixture is admitted to the chamber 9 through the intake pipe 12, the charge preferably having been previously mixed or co-mingled in a suitable carbureter (not shown). The valve 5 is provided with a stem 15, which is preferably tubular, forming a chamber 16 therein. The valve 5 is normally maintained closed by a spring 19, which bears against the flange 18 and 70 the casing, or by equivalent means. Any desired means may be provided to limit the movement of the valve, a ring 20 secured to the stem 15 by a set screw 21, affording very convenient means for the purpose. As 75 shown, the valve stem 15 is preferably provided with one or more openings 22 therethrough.

The valve 5 is preferably extended as at 80 24 and formed with a valve seat 25 thereon, upon which seats a valve 26 provided with a stem 28, the valve stem extending through the chamber 16 in the stem 15 of the valve 5. The valve 26 is normally maintained upon its seat 25 by a resilient member or spring 28, which cooperates with the end of the valve stem 15, and a collar 29, which may be secured in place by a pin 30, or its equivalent. The movement of the valve 26 is limited by a collar 31 secured 85 upon the stem by a set screw 32, it being understood that any equivalent means may be employed for the purpose. Preferably within the cylinder is arranged an auxiliary mixer 35, closed at the end 37 and 90 preferably provided on its sides with slots or openings 36 therethrough. The slots or openings, which may be of any form or size, are preferably omitted at the bottom 45 of the mixer. Arranged within the mixer, I also preferably provide a spreader or distributor 38, which may be secured in position in any desired way, as shown, it is 95 flanged at 39 and secured to the casing 8 by screws 40. The mixer is more fully explained in my application for Letters Patent for mixers or the like, filed herewith.

The operation of the device described is substantially as follows: The mixture is admitted through the intake pipe 12 into the 110

2
chamber 9, and thence passes by the valve 5 into the mixer 35, the valve 5 being operated either from the suction of the engine or mechanically, as desired. At substantially the same time that the valve 5 is opened the valve 26 is opened, and air is drawn in through the openings 22 to the chamber 16, and past the valve 26 into the mixer, where the same meets the mixture from the chamber 9, the mixture and air passing by the baffle or spreader 38, and thence through the openings 36, the air and mixture, or charge, being thoroughly mixed or co-mingled again before firing, a very efficient charge being the result. If there are any particles of hydro-carbon unmixed before entering the mixture, they are thoroughly co-mixed before being fired, and in the case of certain hydro-carbons, where a certain amount of pre-heating is desirable, the same are pre-heated in the mixer 35. By omitting the openings in the lower side of the mixer, when the same is in the position, as shown, any small particles of hydro-carbon are pre-heated and fully mixed with air before entering the combustion chamber. It will be seen that, broadly, the invention consists in providing means for supplying a predetermined amount of air to the mixture, and thoroughly mixing the same therewith before firing.

Referring to Fig. 3, in which another form of my device is shown, 1 represents the cylinder as before, 2 the water jacket, 3 the water jacket space, and 4 the intake port. At the port I preferably arrange a casing 41, similar to that heretofore described, provided with a valve seat 45, upon which seats the valve 46 provided with a stem 47 suitably connected thereto. As shown, the stem 47 is connected to the valve 46 by substantially a yoke 48, and which is arranged to be secured upon the extended part 45 of the valve, there being openings 59, as shown. The valve 46 may be normally maintained upon its seat by a resilient member 50 engaging the collar 51 of the casing, 62 being a collar secured to the stem by a set screw 53, or the equivalent, similar to the other valve described. The valve 46 is provided with a valve seat 54, upon which seats a valve 55 provided with a hollow stem 56, 58 being the passageway or opening through the same. The valve 55 is normally maintained upon its seat by a resilient member 57, or its equivalent for the purpose. The valve 46 may be arranged to be opened or operated either by the suction of the engine or by mechanical means (not shown). The stem 56 is preferably extended as at 60 and arranged to co-operate with a stop 61 carried by a bracket 64, which may be secured to the casing in any desired way, as shown by a screw 65. The stop 61 is preferably adjustable, and may

be made in any suitable way. As shown, it is provided with a screw end 62 and arranged at 63 for convenience in operating, so that by turning the stop in one direction or the other, the movement or travel of the valve 55 may be controlled. The intake port is shown provided with a mixer 35 and spreader 38, similar to that previously described. The operation of the device is substantially as follows: The mixture is admitted through the intake pipe 66 into the chamber 42, where it is drawn into the mixer 35. Before the valve 46, however, reaches the end of its travel and fully opens, the arm 60 engages the stop 61 so that the valve 55 is raised from its seat. Air is then drawn in by suction through the duct 58 in the stem 56, passes between the valve 55 and its seat 54 through the opening 59 into the chamber 42, whence it is drawn in with the ingoing mixture into the mixer 35, and the air and mixture thoroughly mixed in passing through the openings 36. Any hydro-carbon which has not been thoroughly mixed previously in the carburetor, or any excess hydro-carbon, is mixed with the additional air and an efficient mixture discharged into the combustion chamber of the engine for firing.

In Fig. 4 I show a 2-cycle engine cylinder equipped with my device. Referring to the figure, 68 represents the cylinder wall provided with its water jacket 69 and water space 70, 71 being the intake passage and 72 the intake port. In the water jacket 69, I preferably provide an air port 73, which is controlled by a valve 74. A very simple construction is to provide a casing 75, preferably flanged at 76, which is screwed in the wall 69, the same being formed with a seat for the valve 74. In the casing 75 is provided openings 78. The valve 74 is provided with a stem 79, the valve being normally maintained upon its seat by a resilient member or spring 80, and the travel of the valve being controlled by an arm 81 and stop 83 carried by the bracket 82, similar to the construction shown in Fig. 3. The valve may be operated mechanically, if desired, however, I have not shown means for operating it, as they may be of any suitable form, or the valve may be operated by the suction of the engine. In the intake port 72 in the cylinder wall, I have shown a mixer comprising stops 84 having slots 85 therein, the same being closed at the end, as at 86. The mixer may be secured in the port by engaging the extended part at 87 of the cylinder wall, the same being preferably formed with a space 88 about the mixer. Within the mixer may be arranged a spreader 89, similar to the spreaders 38 herein described. The operation of this form of device is as follows: The mixture is admitted through the intake passage 71, 130

whence it passes into the mixer 84 and is mixed with the desired amount of air, which enters through the holes 78, chamber 77, past the valve 74. The same is thoroughly mixed, passing through the holes 85 into the combustion chamber of the engine. It is of course understood that the casing 75 and valve 74 may be arranged wherever desired, as, for example, in the crank casing, 10 or its equivalent, where the mixture is compressed.

In the construction shown in Fig. 5, 91 represents the engine cylinder and 92 its head, 93 being the usual intake port, which is controlled by a valve 94 arranged to seat on the casing 95. The valve 94 is provided with a stem 97, and is normally maintained upon its seat by the spring or resilient member 99, coöperating with the collar 100 and the casing. 101 is a collar similar to those previously described for limiting the movement of the valve. At the intake port, within the cylinder, may be provided the mixer 102, having openings 103 therethrough. 25 Arranged in the cylinder wall, or in the head, as shown in the head, is provided a port 104, normally controlled by a valve 105, which is arranged to coöperate with a suitable seat on the casing 106. The valve 30 is provided with a stem 105, normally maintained upon its seat by a resilient member 109, engaging the collar 110 and the yoke 108 on the casing, 111 being a collar that serves as a stop, as heretofore described in 35 the other constructions. The operation of this device is as follows: The mixture is admitted through the inlet 98 in the casing, and thence passes through the chamber 96 therein past the valve 94, and out through 40 the openings 103, being thoroughly mixed by the mixer. At the same time it is met by an opposing current of air entering the valve 105, which mixes in with the mixture.

Having thus described my invention, it is obvious that various immaterial modifications may be made in the same without departing from the spirit of my invention, hence I do not wish to be understood as limiting myself to the exact form, construction or combination of parts herein shown and described, or uses mentioned.

What I claim as new and desire to secure by Letters Patent is:—

1. The combination in an internal combustion engine of a cylinder, provided with an intake port, and auxiliary means for admitting air to the interior of the cylinder simultaneously with the admission of the charge therein, and a mixing cylinder with 55 in the engine cylinder and overlying said intake port.

2. In an internal combustion engine, provided with a cylinder having an intake port, the combination of means for admitting air 60 to the interior of the cylinder prior to the

ignition of the charge therein, and a mixing cylinder within the engine cylinder in the path of the charge and air.

3. In an internal combustion engine, a cylinder provided with an intake port, 70 means for controlling the admission of the mixture through said port to the combustion chamber, means for controlling the admission of air to the cylinder simultaneously with the admission of the charge therein, 75 and a cup-shaped shell having side wall openings, the shell being positioned within the engine cylinder and overlying said port.

4. In an internal combustion engine, a cylinder provided with an intake port, 80 means for controlling the admission of the mixture through said port to the combustion chamber, means carried thereby for controlling the admission of air to the cylinder through said port simultaneously with 85 the admission of the charge therein, and a mixer secured to the inner wall of the cylinder and overlying said port.

5. In an internal combustion engine, the combination of means for controlling the 90 passage of a mixture through the intake port, means for controlling the admission of air therethrough, an apertured mixing cylinder within the engine cylinder and a spreader in the mixing cylinder. 95

6. In an internal combustion engine, provided with an intake port, the combination of means for controlling the passage of the mixture through said port, auxiliary means coöperating therewith for controlling the 100 admission of air through said port, and a mixer within the cylinder adjacent said port.

7. In an internal combustion engine, the combination of a cylinder provided with an 105 intake port, a valve for controlling said port, a valve controlling the admission of air through said port, and a mixing member overlying both of said valves.

8. In an internal combustion engine, the 110 combination of a cylinder provided with an intake port, a valve for said port, an auxiliary valve coöperating therewith for controlling the admission of air through said port, and a disk shaped member overlying both valves and having an apertured side wall. 115

9. In a device of the kind described, a cylinder provided with an intake port, a mixer arranged within the cylinder, a valve 120 for controlling the fluid passing through said mixer through said port, and means for supplying the air to said mixer simultaneously with the passage of the mixture therethrough. 125

10. In a device of the kind described and in combination, a cylinder provided with an intake port, a mixer arranged within the cylinder at said port, a controlling valve for said port, and means for admitting air 130

to said mixer simultaneously with the passage of the mixture therethrough.

11. In a device of the kind described and in combination, a cylinder provided with an intake port, a mixer within the cylinder comprising a shell provided with a plurality of openings therethrough, a spreader arranged within said shell, an intake valve for said port and an auxiliary air valve arranged to coöperate therewith.

12. In a device of the kind described and in combination, a cylinder provided with an intake port, a controlling valve for said port, a stem for said valve, said valve and stem provided with openings therethrough, and means for normally closing said openings, and a mixing chamber within the cylinder common to said valves.

13. In a device of the kind described and in combination, a cylinder provided with

an intake port, a controlling valve for said port provided with a hollow stem, and means for controlling the passage of fluid through said stem.

14. In a device of the kind described and in combination, a cylinder provided with a mixture intake port, a controlling valve for said port provided with a hollow stem, means for controlling the passage of air through said stem, and means for mixing said mixture and air after the same has passed said valve.

In testimony whereof, I have hereunto signed my name in the presence of two subscribing witnesses.

WALTER C. WESTAWAY.
